UNITED STATES PATENT OFFICE.

GEORGE MULLER, OF NEW YORK, N. Y.

EXTENSION-TABLE.

SPECIFICATION forming part of Letters Patent No. 296,434, dated April 8, 1884.

Application filed October 26, 1883. (No model.)

To all whom it may concern.

Be it known that I, GEORGE MULLER, of the city, county, and State of New York, have invented a new and useful Improvement in 5 Tables; and the following is declared to be a description of the same.

Tables have heretofore been made having drop-leaves and swinging legs for supporting the same.

10 My invention relates to this class of tables; and it consists in the particular manner of constructing the sliding support for the moving legs and the shelves therewith connected.

I prefer to make my improved table of hexagonal shape when fully extended, and I employ six legs, two of which, together with their frames and shelves, slide, the four others being connected firmly with the side and end frames and main part of the table-top, and I 15 employ drawers which are placed in this portion of the table. The table-top is made in three parts, the side leaves being hinged to the oblong central portion, and these side leaves are allowed to hang perpendicularly 20 with the sides of the table after the sliding legs have been closed against the oblong central portion of the table.

In the drawings, Figure 1 is an elevation of the table complete and extended. Fig. 2 is a 25 sectional plan of the same at *y y*. Fig. 3 is a section at the line *x x*, and Fig. 4 represents the end of one of the shelves and a section of the leg and slide.

The table is composed of the legs *a b c d e f*. 30 The legs *a b c d* are connected by the side frames, *g g'*, and end frames, *h h'*, and the table-top *k* is also secured to these legs and frames, and the table-drawers *o o'* slide between the side frames, *g g'*, in the usual grooved ways or 35 ledges. The leaves *n n'* are hinged to the edges of the table-top *k*. To the leg *e* is secured one of the sliding frames composed of the perpendicular partition *l* and horizontal shelf *m*. To the leg *f* is secured the other and 40 similar frame, composed of the slide-partition *l'* and shelf *m'*. The shelves *m m'* slide at their ends in grooves in the inner side of the end

frames, *h h'*, and said shelves are wider between said end frames, *h h'*, and are notched to form stops that bear against the legs *a c* and *b d* when the sides are drawn out to their full limit. It will be noticed that the slide-partition *l'* is deeper than the slide-partition *l*, 50 bringing the shelf *m'* lower than *m*, and that its ends slide in lower grooves. The side frames, *g g'*, are slotted perpendicularly for the passage of the slide-partitions *l l'*, and horizontally for the passage of the shelves *m m'*. Upon the under side of the table-top *k* there are secured grooved strips *r*, and these strips 55 are located between the side frames, *g g'*, and the slide-partitions *l l'* are made with beaded upper edges at *s s'*, and these beaded edges are held by and slide between the grooved strips *r*, so that the parts are thereby kept 60 steadily and truly in place, and the table is thus made firm and reliable.

The shelves *m m'* may be utilized for receiving and holding dishes, cards, or any small articles, and the drawers *o o'* may be divided 65 by boxes or partitions in any desired manner, to hold various games, &c.

I claim as my invention—

1. The combination, in a table, with the legs *a b c d*, side frames, *g g'*, end frames, *h h'*, top 70 *k*, and grooved strips *r*, of the legs *e f*, slide-partitions *l l'* and shelves *m m'*, and hinged leaves *n n'*, the parts being constructed and arranged so that the said slide-partitions and shelves can be pushed into the body of the 75 table to allow the leaves to fall, as set forth.

2. In a table, the combination, with the legs *e f*, and slide-partitions *l l'* and shelves *m m'*, of the grooved strips *r*, the side frames, *g g'*, slotted for the passage of the slide-partitions, and 80 the end pieces, *h h'*, grooved for the ends of the shelves *m m'* to slide in one above the other, substantially as and for the purposes set forth.

Signed by me this 22d day of October, A. D. 1883.

GEORGE MULLER.
